PLATE OR SIMILAR ARTICLE

Frank J. Benes, Lancaster, Ohio, assignor to Anchor Hocking Glass Corporation, Lancaster, Ohio, a corporation of Delaware

Continuation-in-part of design application Ser. No. 9,173, Oct. 26, 1967. This application Aug. 29, 1968, Ser. No. 13,316

Term of patent 14 years

Int. Cl. D7—01

U.S. Cl. D36—2

FIG. 1 is a side elevational view of a plate or similar article showing my new design;

FIG. 2 is a top plan view, it being understood that the ornamentation shown is continuous about the entire periphery of the plate in the path indicated;

FIG. 3 is a sectional view taken along line 3—3 of FIG. 1;

FIG. 4 is a side elevational view of a plate or similar article showing another embodiment of my new design;

FIG. 5 is a sectional view taken along line 5—5 of FIG. 4; and

FIG. 6 is a developed plan view of the ornamentation.

The present application is a continuation-in-part of co-pending U.S. design patent application Ser. No. D. 9,173 filed Oct. 26, 1967, now abandoned.

I claim:

The ornamental design for a plate or similar article, substantially as shown and described.
